(57) **CLAIM**

The ornamental design for a heel protector, as shown and described.

DESCRIPTION

FIG. 1 is a perspective view of a first embodiment of a heel protector showing my new design.

FIG. 2 illustrates a perspective view thereof in use on a shoe heel.

FIG. 3 is a front elevational view thereof. Rear elevational, left-side elevational, and right-side elevational views thereof are identical to the front elevational view.

FIG. 4 is a top plan view thereof.

FIG. 5 is a bottom plan view thereof.

FIG. 6 is another bottom plan view thereof in a different environment.

FIG. 7 is another embodiment of a bottom plan view thereof; and,

FIG. 8 is another bottom plan view thereof in a different environment.

The evenly broken lines throughout the drawings indicate environmental and optional features such as treads and grips, that form no part of the claimed design.
